Patented July 1, 1975

235,600

COMBINED ESCUTCHEON PLATE AND SUPPORTING POST

Raymond U. H. Tegner, Lodi, Wis., assignor to Amerock Corporation, Rockford, Ill.

Filed Dec. 26, 1973, Ser. No. 427,838

Term of patent 14 years

Int. Cl. D6—99

U.S. Cl. D6—86

FIG. 1 is a front view of a combined escutcheon plate and supporting post incorporating my new design.

FIG. 2 is a side view as seen from the right of FIG. 1.

FIG. 3 is an end view as seen from the bottom of FIG. 1.

FIG. 4 is a sectional view taken along the line 4—4 in FIG. 1.

FIG. 5 is a sectional view taken along the line 5—5 in FIG. 1.

I claim:

The ornamental design for combined escutcheon plate and supporting post, as shown.
